UNITED STATES PATENT OFFICE.

LUCIUS L. TAYLOR, OF WAUPUN, WISCONSIN.

DESIGN FOR AN AIR-INJECTOR FOR PUMPS.

59,877.

Specification for Design.

Patented Nov. 29, 1921.

Application filed October 6, 1917. Serial No. 195,202. Term of patent 14 years.

To all whom it may concern:

Be it known that I, LUCIUS L. TAYLOR, a citizen of the United States, residing at Waupun, in the county of Dodge and State of Wisconsin, have invented a new, original, and ornamental Design for Air-Injectors for Pumps, of which the following is a specification, reference being had to the accompanying drawing, forming part thereof.

In the drawings—

Figure 1 is a top plan view of an air injector, showing my new design;

Fig. 2 is a perspective view showing my new design.

Fig. 3 is a side elevation.

I claim:

The ornamental design for an air injector for pumps, as shown.

In testimony that I claim the foregoing I have hereunto set my hand at Waupun, in the county of Dodge and State of Wisconsin.

LUCIUS L. TAYLOR.
